REINFORCED LIGHTWEIGHT CASING
STRUCTURE FOR LUGGAGE

Irving S. Diamond, New York, N. Y.

Application February 18, 1952, Serial No. 272,022

2 Claims. (Cl. 190—49)

1

This invention relates to the construction of what is referred to as lightweight or airplane luggage, wherein a box-like casing of lightweight construction, such, for example, as a balsa casing is used. More particularly, the invention deals with means for reinforcing lightweight casings of the kind under consideration, so as to give strength and rigidity to the casing and to enable the casing to withstand stresses and strains to which the same is subjected in use and handling thereof.

The novel features of the invention will be best understood from the following description, when taken together with the accompanying drawing, in which certain embodiments of the invention are disclosed and, in which, the separate parts are designated by suitable reference characters in each of the views and, in which:

Fig. 1 is a perspective view of the casing of a piece of luggage, with part of the construction broken away and illustrating my improved reinforcement therein.

Fig. 2 is an enlarged sectional view partially on the line 2—2 of Fig. 1 of the drawing.

Fig. 3 is a perspective view of an assembled frame unit as used in reinforcing the cover portion of a casing.

Fig. 4 is a face view of one end portion of a strip, from which the reinforcements or reinforcing frames are formed; and

Fig. 5 is an enlarged sectional view illustrating a modified form of construction.

In luggage of the type and kind under consideration, the same is subjected to abusive handleings, particularly in packing and storing the luggage in airplanes and such handling has resulted in quick breakdowns of luggage of the kind under consideration. The purpose of my invention is to construct a light piece of luggage and provide a lightweight and, yet, strong and durable reinforcements at all corner portions of the resulting luggage, so as to enable the same to withstand the rough handling to which luggage of the type and kind under consideration is subjected, thus producing longer use life of luggage of this kind.

In the accompanying drawing, no attempt has been made to show the finished facings, linings, etc. of the luggage but, instead, the skeleton casing of the luggage is illustrated together with my improved means of reinforcing such casing construction.

In Fig. 1 of the drawing, I have shown, in perspective, the main box or compartment part 10 of a luggage casing and at 11 the cover part. These

2

parts will be constructed of sheets and strips of wood or other lightweight material, glued or otherwise secured together and, at 12 and 13, note Fig. 2, I have shown parts of what may be termed reinforcing cover frames for reinforcing the casing 10 and cover 11.

The reinforcing frames 12 and 13 can be produced as preassembled units, for example, the cover frame unit 13' shown in Fig. 3 or be produced simply from a series of strips cut into predetermined lengths and adhesively secured to the inner surfaces of the parts 10 and 11, so that, when they are secured into position, resulting corner frames, such as 12 and 13, will result.

Considering Fig. 1 of the drawing, it will clearly appear that the frame 12 will comprise two long strips extending along the long corner portions 14 and 15 of the casing part 10 and part of one of these long strips is indicated at 16 extending along the corner 14. At this time, it may be well to state that all of the strips employed are of the same general cross-sectional form or, in other words, are L-shaped or of angle iron cross-sectional form, thus disposing one side of the strip on one wall and the other side of the strip on a wall extending at right angles to the first wall. All of the strips have bevelled ends, as for example, the end 17, noted in Fig. 4 of the drawing, in which figure a face view of the strip 16, for example, is shown. The bevels 17 are at 45° so that all of the strips employed will mesh where they intersect.

Returning now to Fig. 1 of the drawing, I have shown at 18 a part of one of the strips used in forming one of the narrow side corners, the corner 19 of the part 10, the opposed corner 20 having a similar strip. Extending upwardly over each of the vertical corners of the casing part 10 are riser strips 21, part of one of which is indicated in Fig. 1 of the drawing. One of the strips 21 is shown in section in Fig. 2 of the drawing and it will be noted that the upper edge of the strip 21 is flush with the upper edge 22 of the casing part 10 and will, thus, abut the depending strip 23 of the frame 13.

In Fig. 3 of the drawing, I have shown a preassembled frame designated by the reference character 13' and, in this figure, the depending corner portions 23' would be equivalent to the corner strips 23, as shown in Fig. 2.

In Fig. 2, I have shown at 24 one of the long strips of the reinforcing frame of the cover 11, that is to say, the strip extending along the front corner 25 of Fig. 1. A complete frame construction will prevail in the cover 11 but, as this

frame is not otherwise shown in Fig. 1, reference will be made to Fig. 3, which shows an equivalent frame, but in a preassembled form. In other words, in Fig. 3, 24' would represent a strip, similar to the strip 24, 25' the opposing side strip, and at 26' and 27' I have shown the narrow end strips. The bevelled ends of all of the strips, as seen in Fig. 3 of the drawing, will abut and will be welded or otherwise secured together in forming the resulting frame and this frame, as assembled, can then be placed in a cover part, similar to the cover 11, and cemented in position by the use of a suitable adhesive or cement. A rubber cement can be used for this purpose. On the other hand, in forming the reinforcing frames, the separate strips cut to the desired length can be directly cemented in the case or casing parts 10 and 11 and, when so cemented in position, a resulting reinforcing frame will be provided.

It will be understood that the frame of the casing part 10 can also be constructed in the manner of the frame 26' of Fig. 3 or formed by individually cementing the respective strips of the frame in position. At the lower portion of Fig. 2 of the drawing, I have indicated, at 16', a side strip, similar to the strip 16. In other words, the unit frame of the casing 10 would be identical to that shown in Fig. 3, except for the length of the raised corner portions, one of which is illustrated at 21 in Fig. 2 of the drawing.

In constructing the case parts, preparatory to the application of the finishings and linings therefor, an angleiron frame 28 of any suitable construction will be secured to the inner surface of the case part 10, so as to provide a raised annular flange portion, as at 29, to aline and position the cover 11 on the case part 10, as in other luggage of this type and kind. The strip 28 also serves to reinforce the juncture between the parts 10 and 11, as will be apparent.

In Fig. 5 of the drawing, I have shown a slight modification, wherein a suitable solder or the like 30 can be utilized at the abutting edges 31 of two strips 32, 33, as well as at the corner portion, so as to round or fillet the corner portion in the manner diagrammatically illustrated. This construction will be utilized when the strips are individually cemented to the case parts and serve to care for any slight irregularities that may exist at the abutment of the strips and, further, to strengthen and bind abutting edges of the strips.

It will be understood that the strips employed or the frames produced by said strips can be

composed of thin lightweight material of any type and kind such, for example, as metal, plastic or fibre strips and these strips are preferably of thin walled construction so as to maintain the maximum capacity in the resulting luggage or case for storage of clothing or other articles therein. Further, this construction materially reduces the overall weight of the resulting luggage.

Having fully described my invention what I claim as new and desire to secure by Letters Patent is:

1. In luggage of the character described, employing two casing parts, each part being defined by side, top, bottom and end walls joined in corner portions, means for reinforcing inner surfaces of the corner portions of said parts, said means comprising a plurality of thin independent strips of angular cross-sectional form throughout their length and extending along and adhesively secured to corners of said walls, and said strips having common bevelled ends intersecting and abutting at corner portions of the casing parts.

2. In luggage of the character described, employing two case parts having corners defined by angularly disposed walls of the case parts, means arranged on inner surfaces of the case parts at said corners for reinforcing the case parts, said means comprising thin wall independent strips having angularly disposed sides arranged upon and adhesively secured to the angularly disposed walls of the case parts at said corners, end portions of said strips having abutting angular edges, predetermined strips extending to and being flush with adjacent edges of the case parts, and means secured to one case part for alining the other case part thereon.
